VACUUM CLEANER

Ernst Faber, Stuttgart, Germany

Application September 17, 1935, Serial No. 40,905
In Germany January 4, 1935

8 Claims. (Cl. 230—232)

My invention relates to vacuum cleaners and has for one of its objects to provide means whereby the sound generated through the operation of the device is deadened to a considerable extent.

With this and other objects in view I will now describe my invention with reference to the drawing affixed to this specification and forming part thereof which illustrates the rear half of a vacuum cleaner embodying my invention in diagrammatic axial section by way of example.

Referring to the drawing, 1 is the outer shell of the vacuum cleaner which preferably consists of artificial resin or some other sound deadening material and 2 is the filter bag into which is sucked the air, laden with the dust, which enters through an inlet (not shown). 3 is a casing open at both ends and held in place in the shell by means of the rubber ring 4 abutting against a ring 22 of artificial resin and a cap 5, which will be referred to in detail farther below. 6 is the electromotor driving the fan enclosed in the casing, the shaft 7 of the motor being supported in ball bearings 8 located in a box 9. 10 is a cover fixed to the front end of the shell 1 by means of screw bolts 11, this cover being formed of artificial resin or some other suitable material having sound deadening and insulating properties. 12 is a short inwardly directed tube surrounding the exhaust opening 13 of the cover and 14 is a fine-meshed wire gauze or fabric cylinder or sleeve mounted on this tube and forming a screen. 5 is the cap placed on this cylinder and surrounding same with a clearance and 15 is a rubber block inserted between the bearing box 9 and the cap 5. Between this elastic block 15 and the cap 5 is inserted the central portion of a shield 16 which is open sideways of the casing 3 and acts as an air guide, which is thus held in position between the rubber block 15 and the cap 5 which latter is fixed to and spaced from the cover 10 by means of spacing blocks 17.

The rear portion of the casing 3 tapers inwardly at 18 leaving a wide passage 24 for the air between its inner edge 19 and the bearing box 9. 20 is a ring-shaped layer of felt or some other sound deadening material coating the inner face of the rear portion 18 of the casing and 21 is a cylindrical layer of felt or some other textile material coating the inner cylindrical portion of the shield 16.

In the operation of the device the air is sucked through the filter bag 2, in which the dust is deposited, and the clean air further flows past the motor 6 enclosed by the casing 3 and in the di-

rection of the arrows through the passage between the parts 16 and 18 into the hollow cover 10 and through the passage between the cap 5 and the cover and through the screen 14 into exhaust 13 as indicated by the arrows. The air does not anywhere strike a side wall of the shell 1, being prevented from doing so by the casing 3 and by the shield 16 which twice reverses the direction and thereby alters the sectional area of the air current.

The sheet metal casing 3 being supported, together with the motor and fan enclosed therein, between the thick rubber ring 4 and the rubber cushion 15 will not give rise to any vibrations which might create loud noise. Any sound is further deadened quite particularly by the outer shell and the cylindrical sleeve 14 covering the exhaust 13 and by the tortuous path formed for the air between the parts 16 and 18 on the one hand and 5 and 10 on the other hand. A further deadening of sound is produced by the repeated change of the cross-sectional areas traversed by the air current. The elastic mounting of the motor and fan unit fixed to the casing 3, which is suspended between the rubber ring 4 and rubber block 15 prevents the vibrations generated by the motor from being transmitted onto the outer shell and creating sound waves.

The shell 1 and cover 10 being made of artificial resin or the like, apart from deadening sound, also form a protection for the operator's fingers against the action of the electric current.

The arrangement of the parts is such that any vibratory motion of the casing 3, the shield 16 and cap 5 as well as cover 10 are counteracted as far as possible by their elastic support and the air sucked through the apparatus is conducted in a path which further reduces the possibility of sound generation. Owing to its large surface the sleeve-shaped sieve 14 exerts a particularly effective sound-deadening action.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim in the present application to any modification not covered by these claims is expressly reserved.

I claim:—

1. In a vacuum cleaner in combination, a shell

- formed with an air exhaust, a sleeve-shaped screen covering said exhaust, a cap embracing said screen and arranged to lead the air onto said screen in reversed direction, a casing open at both ends within said shell, a motor and fan unit accommodated in said casing, a shield embracing said casing and arranged to twice reverse the direction of the air, which leaves the casing, and elastic means supporting said casing and shield. 5
2. In a vacuum cleaner in combination, a shell formed with an air exhaust, a sleeve-shaped screen covering said exhaust, a casing open at both ends within said shell, a motor and fan unit accommodated in said casing, a cap-shaped shield covering the end wall and axial exhaust opening of said casing and arranged to twice reverse the direction of the air, which leaves the casing, and elastic means supporting said casing in said shell. 10
3. In a vacuum cleaner in combination, a shell of insulating material, a cover of insulating material closing one end of said shell and being formed with an exhaust, a sleeve-shaped screen covering said exhaust, a casing open at both ends within said shell, a motor and fan unit accommodated in said casing, a cap-shaped shield covering the end wall and axial exhaust opening of said casing and arranged to twice reverse the direction of the air, which leaves the casing, and elastic means supporting said casing in said shell. 15
4. In a vacuum cleaner in combination, a shell formed with an air exhaust, a sleeve-shaped screen covering said exhaust, a cap embracing said screen and arranged to lead the air onto said screen in reversed direction, a casing open at both ends within said shell, a motor and fan unit accommodated in said casing, a cap-shaped shield covering the end wall and axial exhaust opening of said casing and arranged to twice reverse the direction of the air, which leaves the casing, and elastic means between said casing and said shell on the one and said cap on the other hand supporting said casing. 20
5. In a vacuum cleaner in combination, a shell formed with an air exhaust, a sleeve-shaped screen covering said exhaust, a cap embracing said screen and arranged to lead the air onto said screen in reversed direction, a casing open at both ends within said shell, a motor and fan unit accommodated in said casing, a cap-shaped shield covering the end wall and axial exhaust opening of said casing and arranged to twice reverse the direction of the air. 25
6. In a vacuum cleaner in combination, a shell formed with an air exhaust, a sleeve-shaped screen covering said exhaust, a cap embracing said screen and arranged to lead the air onto said screen in reversed direction, a casing open at both ends within said shell, a motor and fan unit accommodated in said casing, an elastic supporting means inserted between said casing and said shell and an elastic insertion between said motor and said cap. 30
7. In a vacuum cleaner in combination, a shell formed with an air exhaust, a sleeve-shaped screen covering said exhaust, a cap embracing said screen and arranged to lead the air onto said screen in reversed direction, a casing open at both ends within said shell, a coating of sound deadening material on the rear portion of said casing, a motor and fan unit accommodated in said casing, an elastic supporting means inserted between said casing and said shell, an elastic insertion between said motor and said cap, joined to said latter elastic insertion, a cap-shaped shield covering the end wall and axial exhaust opening of said casing and arranged to twice reverse the direction of the air leaving said casing. 35
8. In a vacuum cleaner in combination, a shell formed with an air exhaust opening, an inwardly directed tubular member surrounding said exhaust opening, a sleeve shaped screen mounted on and surrounding said tubular member, means for guiding a radially inwardly directed air current onto the outer wall of said screen, a casing open at both ends within said shell, a motor and fan unit accommodated in said casing and a cap-shaped shield covering the end wall and axial exhaust opening of said casing and arranged to twice reverse the direction of the air. 40

ERNST FABER.
